CLAIM

The ornamental design for a storage container, as shown and described.

DESCRIPTION

FIG. 1 is a perspective view of a storage container showing my new design;

FIG. 2 is a front elevational view thereof;

FIG. 3 is a rear elevational view thereof;

FIG. 4 is a left side perspective view thereof;

FIG. 5 is a right side perspective view thereof;

FIG. 6 is a top plan view thereof;

FIG. 7 is a bottom plan view thereof;

FIG. 8 is another perspective view thereof, showing the container in use;

FIG. 9 is another perspective view thereof, with the container lid opened; and,

FIG. 10 is another perspective view thereof, showing the container lid opened and the container in use.

The broken lines showing in a hand, a bottle and a bucket in FIGS. 8, 9, 10 are for the purpose of illustrating environment and form no part of the claimed design. The broken lines shown in the interior in FIGS. 9 and 10 are shown portions of the container and form no part of the claimed design.
